Specification for Design.

Patented Feb. 1, 1921.

Application filed August 9, 1920. Serial No. 402,432. Term of patent 14 years.

To all whom it may concern:

Be it known that we, MYRON J. BREITEN-
STEIN and MILTON G. MARTIN, both citizens
of the United States, residents at Stevens
Point, in the county of Portage and State
of Wisconsin, have invented a new, original,
and ornamental Design for Toy Cars, of
which the following is a specification, ref-
erence being had to the accompanying draw-
ing, forming part thereof.

Figure 1 represents a side elevational
view of our improved vehicle, and

Fig. 2 represents a top plan view.

We claim:

The ornamental design for a toy car, as
shown.

In testimony that we claim the foregoing
we have hereunto set our hands at Stevens
Point, in the county of Portage and State
of Wisconsin.

MYRON J. BREITENSTEIN.
MILTON G. MARTIN.
